SILL HEATER CABINET CONSTRUCTION

Clyde W. Colby, East Cleveland, Ohio

Application July 22, 1931, Serial No. 552,444

4 Claims. (Cl. 72—0.5)

This invention relates to improvements in building construction units and more particularly to that type adapted for incorporation in the exterior wall of a building during the building construction and comprising that portion of the wall running from floor to ceiling of one story of the building at a window of that floor. The unit then comprises a window frame and therebelow a wall panel having an outside masonry spandrel and an inside wall cabinet. It is contemplated that heating and ventilating means for the building be incorporated in those units which enter the construction thereof; and generally the object of this invention is to provide improvements in the functioning of such a unit as a ventilating device.

More particularly an object of the invention is to provide improved tie means between the wall cabinet and the masonry spandrel portions of the wall panel, adapted for convenient establishment as the spandrel is laid.

Another object of the invention is to so arrange the parts that fresh air for ventilation will be had by infiltration through the material of the spandrel and will thus be filtered thereby.

Another object of the invention is to provide a unique arrangement whereby the air to be heated may have varying proportions of fresh and recirculated air and finally an object of the invention is to provide means for modifying the humidity of the fresh air taken in, by removing an excess portion of moisture from the fresh air, and subsequently returning said moisture to incoming air when the humidity thereof is lower than before.

The exact nature of this invention together with further objects and advantages thereof will be apparent from the following description taken in connection with the accompanying drawing, in which Fig. 1 is a view in elevation of an embodiment of my invention taken from the inside, and parts being broken away to show details of construction; Fig. 2 is an enlarged section taken transversely of the wall as in the plane of line 2—2, Fig. 1; Fig. 3 is a rear view of the spandrel portion of the unit, that is, a view from the inside of the building with the cabinet removed; Fig. 4 is a horizontal section as in the plane of line 4—4, Fig. 2; and Fig. 5 is a perspective detail of the air control dampers employed.

With reference now to the drawing 1 is a window frame portion of the unit, which has a sill portion 2 and therebelow an integral cabinet having a front facing panel 3 adapted to lie flush or substantially so with the inside face of the wall of the building in which the unit is installed. It

will be appreciated that the construction of the parts described is generally of sheet metal. On the outer face of the wall and running up to the sill 2, is a masonry spandrel, of thickness such as that indicated at 4. For the purpose of tying together the cabinet and spandrel a number of braces 5 are provided as of the T-section indicated. For each brace a number of lugs 6 are provided each having an opening to receive its brace and slidably therealong. Each lug has a bond member 7 as of corrugated metal extending toward the spandrel to lie between courses thereof. Thus, as the courses of the spandrel are laid an occasional lug is slid over each brace and embedded in the mortar; so that ultimately each brace 5 is secured in vertical position back of the spandrel and there firmly held by a number of lugs 6 as indicated Figs. 2, 3 and 4.

The cabinet has a rear panel member 8 which may be secured to the braces 5 in any convenient manner, such as one including the hook section 9 over the ends of the braces. The panel 8 adjacent its lower extremity has an opening 10. Thus a well 11 is provided between the cabinet and the spandrel, so that infiltration through the spandrel may move downwardly in the well 11, thence through the opening 10 into the cabinet.

The cabinet is built up of a number of parts so designed as to permit of assembly and disassembly after the permanent installation of the braces 5, and preferably also a base container portion 12 set into the floor as shown in Fig. 2. Within the confines of the wall cabinet between the front panel 3 and the rear panel 8 thereof, heating means are provided, together with fan means for effecting air flow from the infiltration inlet opening 10 upwardly through the cabinet and out at the top thereof through openings 13 in the panel 3. The details of such means are immaterial but as shown in the drawing these means may include a heating radiator 14 and fans 15 driven by a motor 16. The front panel 3 of the wall cabinet is provided with louver openings 17 extending across its bottom and opposite the opening 10. Thus upon operation of the fan a flow of air will be set up as indicated by the arrows, Fig. 2, from the openings 10 and 17, past the heating means 14 and out through the openings 13.

That the relative amounts of flow through the openings 10 and 17 may be controlled, dampers 10a are provided for the opening 10 and dampers 17a for the louver openings 17. As indicated Fig. 5, the dampers of the two rows thereof are so interconnected as by a link 18 that the dampers 17a will be caused to close as the dampers 10a are

opened and vice versa. That adjustment of the dampers may be had a handle 19 extending through the panel 3 has connection with the spindle 20 which actuates the dampers, through 5 a suitable mechanism such as that shown and including the link 21.

That excess moisture may be removed from the infiltration, to be later added to the infiltration when the latter is dry, hygrometric means are 10 provided. Such means may be merely sand or the like at the bottom of the well 11 as at 22 and in the base portion 12 of the cabinet as indicated at 23. This sand will act as a stabilizer of 15 humidity conditions, taking up moisture when there is too much thereof, and later giving back the same moisture when the air is too dry.

What I claim is:

1. An exterior building-wall panel for the purpose described and comprising a thin outside masonry spandrel and inside wall cabinet means 20 arranged to provide an enclosure spaced from said spandrel by an inverted well, with an opening connecting the bottom parts of said well and said enclosure, said cabinet having an elevated 25 discharge opening, heating means in said enclosure, and hygrometric means arranged adjacent said connecting opening to be effective upon air flowing therethrough.
2. An exterior building-wall panel for the purpose described and comprising a thin outside masonry spandrel and inside wall cabinet means 30

arranged to provide an enclosure spaced from said spandrel by an inverted well, with an opening connecting the bottom parts of said well and said enclosure, said cabinet having an elevated discharge opening, heating means in said enclosure, 5 said cabinet having a base container portion adjacent said connecting opening, and hygrometric means in said container.

3. Means for mounting inside wall cabinet means in spaced relation with an outside masonry 10 spandrel to provide a well enclosure therebetween, said mounting means comprising a plurality of vertically spaced bond members having parts laid between courses of said spandrel, each bond member having a lug and each lug having a brace-receiving opening, a vertical brace disposed in 15 said openings for sliding lengthwise adjustment therein, said wall cabinet means having a well-defining wall adjacent said brace and secured thereto.

4. Means for securing inside wall cabinet means with an outside spandrel and comprising bond members laid between courses of said spandrel and having lugs extending toward said cabinet means, said lugs having openings, braces engaging 20 said openings to be secured in upstanding position, and hook means rearwardly extending from said cabinet means and engaging the upper 25 extremities of said braces.
